UNITED STATES PATENT OFFICE.

EDWARD M. GETZOFF, OF ELIZABETH, NEW JERSEY, ASSIGNOR TO INTERNATIONAL MOTOR COMPANY, OF NEW YORK, N. Y., A CORPORATION OF DELAWARE.

VAPORIZER HEAT-CONTROLLING MEANS.

Application filed June 25, 1927, Serial No. 201,401. Renewed May 25, 1928.

It has been found advantageous in automotive practice to provide means to heat the intake manifold of the motor so as to completely vaporize the incoming fuel particles.

- 5 A common means of accomplishing this consists in providing a chamber in the intake manifold of the engine and connecting the chamber to the exhaust manifold in such manner that a portion of the heated exhaust 60 gases will be shunted from the main exhaust and through the chamber giving up some of their heat to the incoming mixture. While this practice yields satisfactory results at ordinary engine speeds it has been found that 65 10 the volume of exhaust gases passing through the chamber is not sufficient to make available sufficient heat to maintain the walls of the intake manifold at the temperature necessary to completely volatilize the incoming 70 15 fuel particles when the engine is at idling speeds.

Heretofore it has been proposed to remedy this defect by providing means whereby a greater proportion of the exhaust gases 75 20 would be passed through the vaporizing chamber as the engine speed decreased. Such means have usually comprised a valve in the main exhaust passage which was controlled by a governor on the engine or by the engine 80 25 throttle lever in such a manner that as the engine speed was decreased the main exhaust passage was constricted and a greater proportion of the available exhaust gases thereby constrained to pass through the vaporizing 85 30 chamber. These means, however, have not been found entirely satisfactory because of unnecessary complications of parts and for other reasons.

It is the principal object of this invention 40 45 to control the volume of available exhaust gases passing through the vaporizing chamber in such a manner as to overcome the defects inherent in known constructions. The relative position of the hand brake lever of the vehicle is ordinarily such with respect to 50 55 the main exhaust pipe that the said lever may readily and conveniently be connected with the controlling means in the main exhaust pipe. Accordingly, it is proposed to connect one end of the hand brake lever to a butterfly valve or other controlling means in the exhaust pipe in such manner that when the lever is set the valve will be substantially closed and the major portion of the available exhaust gases will be constrained to pass

through the vaporizing chamber, since the hand brake lever will usually be set when the vehicle is at a standstill and the engine idle. Upon releasing the brake and starting the vehicle the valve will be opened and the major portion of the exhaust gases, which increase in volume with the engine speed, allowed to pass out through the main exhaust pipe, a smaller percentage of the total volume of exhaust gases being required to maintain the necessary temperature in the vaporizing chamber.

For a fuller understanding of the invention reference may be had to the following detailed description thereof which should be read in connection with the accompanying drawings. In the drawings:

Figure 1 is a view in side elevation of so much of a motor vehicle as is necessary to show the invention applied thereto; and

Figure 2 is a view of the exhaust and intake manifold of a motor vehicle showing the manner of controlling the flow of exhaust gases through the vaporizing chamber by means of a hand brake lever.

In the drawings, there is shown the exhaust manifold *a* of an internal combustion engine and the intake manifold *b*. The intake manifold *b* is formed as at *b'* with an enlarged portion through which passes the pipe *b*². The pipe *b*² is adapted to be connected to the exhaust manifold *a* as by means of the elbow *a'*. The exhaust manifold *a* discharges into the exhaust pipe *a*², the short pipe section *a*³ being interposed between the manifold *a* and the pipe *a*². Within the section *a*³ is disposed a butterfly valve *a*⁴ which is adapted to be opened and closed by means of the link *a*⁵. The link *a*⁵ is connected to the rod *c* which is made up of two members *c'*, *c*² for a purpose which will appear more clearly hereinafter. The rod *c* is connected as at *c*³ to the hand brake lever *d* which is adapted to be swung about its pivot point *d'*.

The hand brake lever *d* is illustrated in the drawings in a set or "on" position. The connection between the hand brake lever and the butterfly valve *a*⁴ by means of the rod *c* is such that when the brake lever is in a set position, as shown, the valve will substantially close the passage through the pipe section *a*³. When the brake is released by swinging the lever *d* in the direction of the arrow, the valve *a*⁴ will be open, leaving the

passage through the section a^3 practically unobstructed.

When the vehicle is in operation the hand brake will, of course, be released, leaving the main exhaust line through the section a^3 and the pipe a^2 unobstructed. The major portion of the exhaust gases will therefore pass out through the pipe a^2 . At running speeds, however, the pressure of the exhaust gases within the manifold a is sufficient to cause a portion of them to pass through the elbow a' and the pipe b^2 within the vaporizing chamber b' sufficient to supply the necessary amount of heat to the fuel stream passing through the enlarged portion of the intake manifold. But at idling speeds the pressure of the exhaust gases within the manifold a is not sufficient to cause a great enough portion of them to pass through the pipe b^2 within the vaporizing chamber if the main exhaust line is open. At such times, however, the hand brake will generally be set. The passage through the main exhaust line will therefore be obstructed since the valve a^3 is closed and the major portion of the exhaust gases will be constrained to pass through the pipe b^2 within the vaporizing chamber and out through the auxiliary exhaust b^3 .

In order to prevent damage to the valve a^4 on account of the uncertain position which the lever d may assume when the brake is set the rod c , as previously stated, is formed of two members c' , c^2 and a spring c^4 is interposed therebetween so that should the valve a^4 be completely closed before the lever d has reached the end of its travel the spring c^4 may be compressed, thus preventing undue strains on the valve.

It will now be seen that there has been provided means to control the flow of exhaust gases through the vaporizing chamber in the intake manifold of a motor vehicle such that a greater proportion of the available gases will be constrained to pass through the vaporizing chamber at idling speeds than at running speeds. To accomplish this, use has been made of the hand brake lever which, it is well known, will usually be set when the engine vehicle is idling as, for instance, when the vehicle is at rest. Thus, the efficiency of the engine is greatly increased resulting in decreased wear on moving parts of the engine, such as the cylinder walls, etc. The

means employed are simple, durable and inexpensive, entailing no unnecessary complications of parts.

Nothing which has been said in the foregoing description is intended as a limitation upon the scope of the invention except as may be indicated in the appended claims.

What I claim is:

1. In a motor vehicle having an intake manifold, an exhaust manifold, a vaporizing chamber in the intake manifold, and connections between the exhaust manifold and the vaporizing chamber for heating the latter, means in the exhaust manifold to cause a greater interchange of heat between the exhaust manifold and the chamber upon setting the brake lever of the vehicle than at running speeds of the vehicle.

2. In a motor vehicle having an intake manifold, an exhaust manifold, and a vaporizing chamber comprising an enlarged portion in the intake manifold and a pipe connected with the exhaust manifold passing therethrough, means in the exhaust manifold to cause a greater proportion of exhaust gases to pass through the vaporizing chamber upon setting the hand brake lever of the vehicle than at running speeds of the vehicle comprising, a butterfly valve in the exhaust line, and means connecting the valve with the hand brake lever to close the valve when the hand brake lever is set.

3. In a motor vehicle having an intake manifold, an exhaust manifold, and a vaporizing chamber comprising an enlarged portion in the intake manifold and a pipe connected with the exhaust manifold passing therethrough, means in the exhaust manifold to cause a greater proportion of exhaust gases to pass through the vaporizing chamber upon setting the hand brake lever of the vehicle than at running speeds of the vehicle comprising, a butterfly valve in the exhaust line, a rod connecting the valve with the hand brake lever to close the valve when the hand brake lever is set, and means on the rod to permit further movement of the lever after the valve has been seated without damaging the valve.

This specification signed this 20 day of June, A. D. 1927.

EDWARD M. GETZOFF.
